UNITED STATES PATENT OFFICE.

ALEX GUSTAVE MALMSTROM, OF CHICAGO, ILLINOIS.

CAR-SEAL.

SPECIFICATION forming part of Letters Patent No. 548,568, dated October 22, 1895.

Application filed December 6, 1894. Serial No. 530,952. (No model.)

To all whom it may concern:

Be it known that I, ALEX GUSTAVE MALMSTROM, a citizen of the United States, and a resident of Chicago, Cook county, Illinois, 5 have invented certain new and useful Improvements in Car-Seals, of which the following is a full, clear, and exact description, reference being had to the accompanying drawings, and to the letters of reference marked to thereon.

The object of my invention is to provide a cheaply-constructed car-seal which can be locked by hand without requiring the use of any specially-constructed tool or implement 15 of any kind and which cannot be unlocked except by cutting the loop or breaking the seal.

My invention consists of the usual metallic loop or strap and a seal, in which one end of 20 the loop is originally permanently fastened and which has a pocket that has locking-hooks inserted therein projecting from its sides in such manner that when the originally free perforated end of the strap is inserted in the 25 pocket its withdrawal is prevented, substantially as hereinafter fully described, and as illustrated in the drawings, in which—

Figure 1 is a perspective view of my invention. Fig. 2 is a longitudinal central view of 30 the seal with the ends of the loop secured therein, taken on an enlarged scale. Fig. 3 is a detail view showing, on an enlarged scale, the detached originally free end of the loop or strap; and Fig. 4 is a detail view, on an enlarged scale, of the U-shaped metallic strip 35 located within the pocket of said seal.

Referring to the drawings, A represents a narrow strap or loop of sheet metal, one end of which is permanently secured in the seal 40 B, preferably by being molded therewith, as shown in the drawings, and the other end C of which is provided with two openings a and b. These openings a and b are preferably arranged in longitudinal alignment, and the 45 opening b nearest the end thereof is preferably longer than the other.

The nature of my invention is such that by inserting end C, which is originally free, into the pocket of the seal B it is caught and locked 50 therein, so that it cannot be withdrawn except by breaking the seal. This seal B is

preferably of a rectangular shape, and it is recessed longitudinally from one end, so as to form a pocket d of such width as to freely admit the insertion of end C of the loop. Placed 55 and permanently secured within this pocket is the lock D. This lock consists of a U-shaped strip of sheet metal of about the same width as the pocket d. It is originally made of a single length twice the depth of the pocket, 60 and it is bent double, so that one of the legs h thus formed will lie flat against one side of said pocket and the other leg k will lie flat against the other broad side thereof in such manner that when the free end of the strap 65 or loop is inserted in the seal it will pass between said legs. Now in order to prevent the withdrawal of end C when inserted in the seal I have provided both of said legs h and k with a hook e and g, respectively, which pref- 70 erably consist of tongues stamped out of said legs, the free ends of which project inward a slight distance and then extend longitudinally toward the closed end of the pocket. When the end C of the loop is pushed into the pocket, 75 it forces the hooks back out of the way; but when the ends of said hooks come next or in register with the openings a and b of said end they spring through them and prevent the withdrawal of said end. I can, if desired, dis- 80 pense with one of said hooks, although I much prefer the use of both. If desired, I can provide one or both of the hooks h and k with a slight spur x near their extremity, which will catch under the end edge of end C or the ad- 85 jacent edge of the opening b, as shown. This serves, after the end C is once caught and held by the hooks, to prevent any longitudi- 90 nal movement of the said end.

What I claim as new is—

1. As an article of manufacture a car-seal consisting of a suitable strap or loop, a suitable metallic seal having a pocket therein, and a U-shaped strip of metal secured in said pocket having a tongue or hook projecting 95 from each leg of the same into and toward the closed end of said pocket and said hooks each being provided with a spur projecting from near its free extremity backward toward its secured end, said strap having one end per- 100 manently secured to said seal and the other provided with an opening therein so that

when thrust in said pocket, said hooks will catch and with the aid of said spurs effectually lock the same.

2. As an article of manufacture a car-seal 5 consisting of a suitable strap or loop, and a suitable metallic seal having a pocket therein, a tongue or hook projecting from each of the broadsides of said pocket in such manner as to follow one another, said tongues or hooks 10 extend and point toward the closed end of said pocket, and near their free extremities

are provided with spurs which point toward the secured end thereof, and said loop having one end permanently secured in said seal, and the other normally free end provided with 15 reference to said hooks, and so that when said end is inserted in the pocket of the seal it is locked therein.
